UNITED STATES PATENT OFFICE.

MAX THOMSEN, OF CHICAGO, ILLINOIS.

FAUCET SPRAY ATTACHMENT.

1,193,086.

Specification of Letters Patent. Patented Aug. 1, 1916.

Application filed March 19, 1914. Serial No. 825,788.

To all whom it may concern:

Be it known that I, MAX THOMSEN, a citizen of the United States, and a resident of the city of Chicago, in the county of Cook and State of Illinois, have invented certain new and useful Improvements in Faucet Spray Attachments; and I do hereby declare that the following is a full, clear, and exact description of the same, reference being had to the accompanying drawings, and to the numerals of reference marked thereon, which form a part of this specification.

This invention relates to a device which may be inserted over the discharge spout of an ordinary faucet to be held frictionally and sealingly thereon, permitting either a concentrated continuous stream to flow therethrough, or a spray through a number of apertures provided for the purpose.

This invention is particularly well adapted for use on faucets in the kitchen, whereby the operation of washing dishes in a pan beneath the faucet may be greatly facilitated, owing to the fact that when it is desired, the dishes may be sprayed and easily cleaned of the soapy water.

It is an object of this invention to construct a device consisting of few parts and simple in operation, whereby either a continuous concentrated stream or a spray may be obtained from a faucet, as desired.

The invention (in a preferred form) is illustrated in the drawings and hereinafter more fully described.

In the drawings: Figure 1 is a conventional side elevation of a faucet, illustrating a device embodying the principles of my invention connected thereto and shown in section. Fig. 2 is a bottom plan view of a device with the closure shown in open position in dotted lines.

As shown in the drawings: The faucet is indicated as a whole by the reference number 1, and is provided, as usual, with a handle 2, and a discharge spout 3. Engaged on the end of the discharge spout 3, is a device comprising a cylindrical casing 4, having an upstanding flange 5, integral therewith, within which is inserted a washer 6, the lower end of which rests upon an inwardly directed flange or lip 7, formed integral with said casing. A partition 8, extends across the interior of said casing 4, and is provided with a plurality of apertures 9, spaced therearound in any conven-

ient manner, and of the same or different sizes, as desired, dependent upon the particular type of spray desired. Said partition 8, is provided with a large aperture 10, in alignment with the passage through said flanged portions 5 and 7, so that when said aperture 10, is open the concentrated stream of water from the spout 3, of the faucet will pass directly therethrough in an uninterrupted manner. For the purpose of obtaining a spray, a closure is provided for said enlarged aperture 10, which may be mounted in any suitable way. In the construction I have shown a circular head 11, which may or may not have apertures therein, as desired, although I have shown it provided with apertures, said head being pivotally held on the under side of said partition by means of a pivot pin 12. An offset and somewhat resilient arm 13, is formed integral with said head 11, and extends outwardly on the opposite side of said pivot pin 12, the offset portion in said arm adapting the same to extend down and around the lower edge of the cylindrical casing into a convenient position for actuation. It is obvious from the position of the pivot pin 12, that the offset portion in said arm 13, only engages the casing when the device is in closed position, as shown in Fig. 2, and owing to the resiliency of the arm and somewhat close frictional engagement with the partition 8, the closure of the device remains in any desired adjusted position. A small stop 14, is secured in the under surface of said partition 8, to limit the movement of said closure head 11, as the same swings into closing position over said aperture 10.

Although I have shown the closure head apertured in the construction illustrated, it is obvious that in the event of use of the device on a faucet through which a stream under great pressure is discharged, it is advisable to use a closure head provided with very few or no apertures, in order that the fluid may be distributed within the casing and more effectually sprayed through the apertures in the partition.

I am aware that various details of construction may be varied through a wide range without departing from the principles of this invention, and I therefore do not purpose limiting the patent granted otherwise than necessitated by the prior art.

I claim as my invention:

The combination with a faucet, of a spray-

ing device releasably attached thereon embracing an apertured spray partition therein, an enlarged aperture therethrough in alinement with the spout of the faucet to permit an uninterrupted stream from the faucet to pass therethrough, and a resilient bar closure pivotally mounted on the under surface of said partition and extending beyond the outer edge of said device to close 10 said enlarged aperture and frictionally en-

gaging the partition to hold said bar closure in any position of adjustment.

In witness whereof I have hereunto subscribed my name in the presence of two subscribing witnesses.

MAX THOMSEN.
